UNITED STATES PATENT OFFICE.

HENRY J. FAUBEL AND WILLIAM ROACH, OF ALLIANCE, OHIO.

ELECTRIC RAILWAY-SIGNAL.

1,194,981.

Specification of Letters Patent. Patented Aug. 15, 1916.

Application filed June 25, 1915. Serial No. 36,377.

To all whom it may concern:

Be it known that we, HENRY J. FAUBEL and WILLIAM ROACH, citizens of the United States, residing at Alliance, in the county of

5 Stark and State of Ohio, have invented new and useful Improvements in Electric Railway-Signals, of which the following is a specification.

This invention relates to electric railway 10 signals.

In carrying out our invention it is our purpose to provide the rails of a track which are seated upon metallic ties, with an electric railway signal, which is actuated by the 15 wheels of the train, and which will be properly insulated from the metallic ties as well as from the rails so that danger of short circuiting will be entirely eliminated.

We also propose to provide a railway signal 20 for tracks secured upon metallic or other electric conducting ties, with a laterally movable contacting bar which is arranged longitudinally with but retained spaced from one of the rails and which is contacted by the wheels of a car to complete the 25 circuit with a signal bell or visible signaling apparatus.

A further object of the invention is to 30 provide an electric signal which shall include a spring pressed laterally movable contact plate or bar which is engaged by the flange of a wheel, and with the said flange, and the rail adjacent which the bar is longitudinally arranged, form a part of 35 an electric circuit to provide for the positive operation of the parts resulting from the interposition between the rail, the contact bar and the flange of the wheel.

A further object of the invention is to 40 provide a device of this character which shall not be affected by ice, snow, dirt or grease, and which will properly direct the flange of a wheel between a contact plate and a rail to insure the proper closing of an 45 electric circuit and the operation of a signal.

A further object of the invention is to 50 provide means for supporting a spring-pressed laterally movable contact bar in proper spaced relation to a rail which is

supported by metallic ties, and which also provides for the ready removal or the ready arrangement of the said contact bar upon the said supports.

A further object of the invention is to 55 provide supporting means for a longitudinally arranged laterally movable spring-pressed contact bar, which is adapted to be sustained in a spaced position with relation to a rail that is sustained upon channelled 60 metallic ties, whereby the said supports may be positioned between the channels of the tie, or connected directly to the rail between the sides of the channelled ties or between the outer sides of two or more adjacent ties. 65

A still further object of the invention is to provide a rail of a track supported upon metallic ties with a longitudinally arranged contact bar which is substantially V-shaped in cross section to permit of the shedding of 70 moisture therefrom, to provide insulated brackets for supporting the bar, to arrange spring pressed members upon the brackets so that the bar will be subjected to a lateral movement in a direction away from the rail, 75 to provide means for regulating the tension of the springs and the space between the bar and the rail, to connect the bar and the rail with an electric circuit that is connected with an electric magnet or solenoid for operating a semaphore or other signal device, 80 and wherein the broken circuit is completed by the flange of a wheel passing between and contacting with a bar and rail.

With the above and other objects in view, 85 the improvement resides in the construction, combination and arrangement of parts set forth in the following specification and falling within the scope of the appended claims.

In the drawings there has been illustrated 90 a simple and satisfactory reduction of the improvement to practice, but the nature of the invention is such that the same is susceptible to many and various embodiments in the details of construction, all of which, 95 however, fall within the scope of the appended claims.

In the drawings: Figure 1 is a plan view of a railway track illustrating the arrangement of our improved contact bar thereon, 100

Fig. 2 is a view approximately on the line 2—2 of Fig. 1, Fig. 3 is a top plan view of a bar supporting bracket, Fig. 4 is a sectional view approximately on the line 4—4 of Fig. 5 illustrating diagrammatically the electric circuit and its connection with a semaphore signal, Fig. 5 is a detail plan view illustrating another manner of supporting and sustaining the contact bar adjacent the rails, Fig. 6 is a sectional view approximately on the line 6—6 of Fig. 5, Fig. 7 is a sectional view approximately on the line 7—7 of Fig. 5, Fig. 8 is a detail plan view illustrating the manner in which the brackets for sustaining the contact bar may be arranged and secured to the substantially U-shaped or channeled metallic ties, Fig. 9 is a sectional view approximately on the line 9—9 of Fig. 8, Fig. 10 is a sectional view approximately on the line 10—10 of Fig. 8, Fig. 11 is a detail plan view illustrating the manner in which the contact bar supporting brackets may be arranged between the sides of the channeled ties and secured to the adjacent ties, Fig. 12 is a sectional view approximately on the line 12—12 of Fig. 11, and Fig. 13 is a sectional view approximately on the line 13—13 of Fig. 11.

Owing to the scarcity of timber great efforts have been made in the art to supplant the ordinary wooden ties by metallic or plastic substance. Properly constructed metallic ties have proven equally efficient and more durable than the wooden ties, but the same have proved deficient upon electric signal devices for the reason that the electric conducting properties possessed thereby result in the short circuiting of energized wires.

It is one of the primary objects of the present invention to connect an electric signal with rails supported upon metallic ties, in such a manner, that danger of short circuiting the wires will be entirely and effectively overcome.

As illustrated by the accompanying drawings we employ metallic ties 1 in the nature of channeled members, forming the same, adjacent their ends, with blocks upon which the rails 2 rest, and the said rails are secured upon the said blocks by metallic retaining elements 3. The ties between and outward of the rail supporting blocks are provided with openings for the escape of moisture therefrom.

In the structure illustrated in the drawings, in Figs. 1 to 4 thereof, we arrange between certain of the ties 1 spaced bracket members 4. Each of these brackets includes a longitudinally extending plate 5, one of the ends of which being formed with a right angular extension 6, the said extension terminating in an angular flange 7 which is shaped to conform to and which is adapted to engage with the underface and the base flange at the outer sides of one of the rails

2. The numeral 8 designates a clip which has its upper portion formed with an angular flange 9 conforming to the cross sectional shape of the inner base flange of the rail and with which it is adapted to engage. 70 The clip includes a straight member depending from the lower and horizontal portion of the flange 9, the said straight member, indicated by the numeral 10, having its end formed with an outturned portion or lug 11 which is adapted to rest upon the plate 5 to contact with the extension 6 of the bracket 4. Passing through suitable openings in the members 10 of the clip 8 and the member 6 of the bracket 4 is a securing element in the nature of a bolt 12 having a nut 13. Interposed between the flanges 7 and 9 of the bracket clip and the base flange as well as a portion of the web of the rail 2 is a sheet of insulating material, indicated by the numeral 14. The plates 5 of the brackets extend inwardly of the track, and the said plates are each formed at their ends and at a suitable distance away from their ends with right angular upwardly extending arms 15—15. These arms have their upper edges bifurcated, the lower walls of the said bifurcations being round, and pivotally secured to one of the said members provided by each of the bifurcations is a bearing or holding member 16. Each of these members is centrally provided with an enlarged portion which fits snugly between the bifurcated ends of the arms 15, and the free ends of each of said members 16 is formed with a centrally reduced portion or tongue 17 that is adapted to be received in a suitable slot in the second member provided by the bifurcation in each of the arms 15. Adapted to 105 pass through the last mentioned member as well as through a suitable opening in the tongue 17 is a removable securing element, preferably in the nature of a cotter pin 18. The members 16 are adapted to sustain in the bearing provided by the bifurcated arms 15 longitudinally movable rods 19, the said rods having their inner ends provided with vertical angular extensions 20 which terminate in outturned substantially horizontally straight feet 21. Removably secured to the feet 21 is a contact bar 22. This bar is substantially V-shaped in cross section, so that moisture will be readily shed therefrom and so that dirt, grease, etc., will not be permitted to accumulate between the same and the head of the rail from which it is spaced. The ends of the bar 22 are rounded inwardly, or away from the rail 2, so that the flange of a car wheel will be directed between the said bar and the said rail. The rods 19, adjacent their angular extensions 20 are provided with a plurality of spaced apertures 23, and passing through one of said apertures is a pin 24. The pin 125

is preferably in the nature of a cotter pin and is adapted to serve as a stop for a washer 25 which is contacted by a spring 26 that surrounds each of the rods 19 and 5 exerts a tension between the outer arms 15 of each of the brackets 4 and the said washers to slide the rods 19 laterally of the rail to bring the contact bar 22 in proper spaced relation to the said rails. This arrangement 10 permits of the adjustment of the springs, and consequently the inward movement of the contact bar toward the rail, so that the flange of a car wheel passing between the rail and bar will readily contact with both 15 the rail and bar, and complete an electric circuit, to operate a signal, in a manner which will presently be described. The arrangement of the rods 19 carrying the contact bar 22, upon the brackets 4, permits of 20 the ready removal or insertion of the said rods upon the brackets, as will be fully understood. It will be also noted that none of the parts of the contact member or its support engage or contact with the rail or 25 with the metallic tie, except the flanged portions of the bracket and clip which are secured to the rail, and which, as previously stated, are insulated from the rail, so that danger of short circuiting of the electric 30 wires (hereinafter to be described) will be effectively obviated. As stated the construction of the bar 22 prevents the accumulation of moisture, etc., thereon, and it is to be understood that the spring pressed rods as 35 well as the bracket supports therefor may be closed by a suitable housing to protect the same from the elements.

The bar 22 may be provided upon its upper face with any desired number of apertures, certain of which will serve as an outlet for any accumulation of moisture, but one of the said apertures is adapted to receive a removable element, preferably in the 40 nature of a screw, which serves as a binding post for a conducting wire 28 which is extended down between the ties beneath the rail outwardly of the track, and which is connected with a solenoid or electromagnet provided in a semaphore stand 29 for actuating 45 a semaphore arm 30 when the circuit, of which the wire 28 provides one member, is completed. The return wire is indicated by the numeral 31 and communicates with a battery 32, and is connected with a binding 50 post 33 secured upon the flange of the rail 2. It is, of course, to be understood that the battery 32 is to be arranged in a suitable well and that the wires are suitably protected by being passed through conduits 55 and also that the semaphore may be arranged any distance from the contact bar 22. It is to be also understood that any number of semaphores and contact bars and 60 electric circuits between the same may be 65 employed, the last mentioned arrangement

being necessary upon a block signal, and it will be further apparent that when the flanges of the wheels of the rolling stock passing over the track, are arranged to contact between the bar 22 and the rail 2 the 70 broken electric circuit is completed and the arm 30 of the semaphore actuated to bring the arm 30 to danger position. Of course, when the wheels of the last car pass the contact bar 22 the semaphore arm 30 will 75 be returned to its initial position.

In Figs. 5 to 7 we have illustrated the brackets 31 which provide bearings for the laterally movable spring pressed rods 32, that carry the contact bar 33, as supported 80 upon wooden blocks 34. These blocks are preferably of a width corresponding with the distance between the sides of the channeled ties 1, but in order to assist in sustaining the said blocks in the ties we force 85 wedge members 35 between the inner faces of the sides of the tie and the outer faces of the sides of the block. In order to insure the insulation of the wooden blocks 34 we surround the same with a sheet of non-conducting material 36, and we secure the blocks between the sides of the tie by transverse connecting elements, preferably in the nature of lag screws 37 which pass through 90 the sides of the tie and enter through the 95 sides of the blocks. These lag screws are also insulated, so that danger of their short circuiting will be effectively overcome. As the laterally movable rods 32 are sustained, upon the brackets 31, above the tie 1, the 100 contact bar 33 is secured directly to the inner and flattened end of each of the said rods 32. Each of the rods 32 is provided with a plurality of orifices 38 for the reception of an adjustable pin 39 which serves as 105 a contact member for the spring 40 to limit and adjust the inward movement of the bar 33 with relation to the rail of the track adjacent which it is positioned. The electric connection between the rail, signal and 110 contact bar is substantially similar to that heretofore described. It is desirable that the brackets may be so constructed as to be readily positioned upon a tie between the sides thereof, without the employment of 115 the blocks above referred to, such construction being illustrated in the remaining figures of the drawings.

In Figs. 8 to 10 we have illustrated bracket members 41 which are adapted to be 120 arranged upon the upper edges and secured between the sides of the channeled ties 1. These brackets each include a substantially rectangular box-like member having the upper edges of its sides provided with out-turned horizontally disposed flanges 42. The width of the box-like structures is substantially equal to the distance between the side members of the channeled ties, and the flanges 42 are adapted to rest upon the up- 125 130

per edges of said sides of the tie. The end walls 43—43 of each of the brackets 41 are formed with registering openings through which is passed a rod 44, the said openings 5 providing journals or bearings for the slideable rods. The rods have their inner ends provided with angular upwardly extending portions 45 which terminate in feet 46 which extend inwardly toward the rail adjacent 10 which the brackets are sustained, and secured to the said feet are the longitudinally disposed substantially cross sectionally V-shaped contact bars 47. The rod 44 is provided with a plurality of apertures for 15 the reception of an adjustable pin 48 which provides a contact member for a spring 49 which surrounds the rod 44 which exerts a tension between the inner end of the bracket 41 and the said pin 48, to slide the contact 20 bar 47 toward the rail and to sustain the same in proper spaced relation with the said rail.

In the remaining figures of the drawings, the brackets 50 are constructed to be arranged between two or more of the adjacent ties, and each of the said brackets comprises a body in the form of a plate 51, said body having its opposite ends formed with upturned flanges 52, these flanges being spaced to equal the distance between the adjacent sides of the ties 1, and the said flanges have their ends formed with outwardly extending horizontally disposed feet 53 which rest upon the upper edges of the tie. The body plate 51 is centrally provided upon its longitudinal edges with upwardly extending members or ears 54—54, said ears having alining openings for the reception of the slideable rods 55. These rods have their ends upturned and provided with horizontal extensions forming supporting elements through which the contact bar 56 is secured. The rods 55, between the ears 54, are provided with a plurality of apertures and passing through one of the apertures is a pin 57 which serves as a stop member for a washer 58. Surrounding the bar and exerting a tension between the washer and one of the ears 54 is a spring 59 which forces the contact bar 56 toward the rail 60.

55 The brackets 41 and 50 have arranged between the sides or flanges thereof as well as between the offset horizontal portions formed with the said sides, sheets of insulating material 61, the said material also contacting with the upper edges of the inner sides of the channeled metallic ties, the side flanges of the brackets as well as the 60 sides of the tie being provided with registering openings, and arranged within the said openings are tubular members constructed of insulated material, indicated by the numerals 62 and passing through the 65 said tubes and compressing the ends there-

of against the sides of the tie are bolts 63 which are provided with securing nuts 64, the said securing nuts compressing the inner edges of the tubes against the inner faces of the sides or flanges of the brackets, so that a proper insulation of the brackets from the metallic ties is thus effectively provided. 70

provided. It is to be understood that the electric circuits in the last mentioned form of the device are substantially similar to that previously described, and also that the circuits may be arranged to sound an audible as well as a visible alarm, if desired, and from the above description, taken in connection with the accompanying drawings, the simplicity of the device, as well as the advantages thereof will, it is thought, be perfectly apparent to those skilled in the art to which such invention appertains without further detailed description.

Having thus described the invention, what we claim is:

1. The combination with a rail supported upon ties, and brackets insulated from the rails and ties, of longitudinally movable spring pressed rods in the brackets, and an angular contact bar secured to the rods and sustained longitudinally of and spaced from the rail.

the rail. 2. The combination with a rail supported upon ties, and brackets insulated from the rail and ties, of removable rods arranged for slideable movement in the brackets, means for limiting the sliding of the said rods, and an angular contact bar secured to the rods and retained thereby in spaced relation to the rail. 100

3. The combination with a rail supported upon ties, and brackets insulated from the rail and ties, of rods arranged for slideable movement in the brackets, means for removably retaining the rods in the brackets, springs for sliding the rods in one direction and toward the rail, means for regulating the tension of the springs and the sliding movement of the rods, and an angular contact bar secured to the rods and sustained thereby in a spaced relation to the rail. 105 110

4. The combination with a rail supported upon ties, and brackets insulated from the rail and ties, spaced arms upon the brackets, of longitudinally movable rods journaled in the said arms, means for removably sustaining said rods in the said journals, springs for moving the rods in one direction and toward the rail, means for regulating the tension of the spring and the said sliding movement of the rods, and an angular contact bar secured to the rods and sustained longitudinally of but spaced from the rail. 115 120 125

5. The combination with a rail, of a longitudinally extending contact bar disposed adjacent the rail, said contact bar having 180

its inner edge pointed and disposed opposite the head of the rail, supports, spring pressed rods slideable in the said supports, means for removably securing the said rods upon the supports, means for adjusting the tension of the springs to regulate the sliding movement of the rods, and said contact bar being secured to said rods.

In testimony whereof we affix our signatures in presence of two witnesses.

HENRY J. FAUBEL.
WILLIAM ROACH.
